B. B. BLOOD,
MODIFIER FOR PHONOGRAPH SOUND BOXES,
APPLICATION FILED MAR. 4, 1920.

1,408,437.

Patented Mar. 7, 1922.

UNITED STATES PATENT OFFICE.

BURR B. BLOOD, OF CHICAGO, ILLINOIS, ASSIGNOR, BY MESNE ASSIGNMENTS, TO JEWEL PHONOPARTS COMPANY, OF CHICAGO, ILLINOIS, A CORPORATION OF ILLINOIS.

MODIFIER FOR PHONOGRAPH SOUND BOXES.

1,408,437.

Specification of Letters Patent. Patented Mar. 7, 1922.

Application filed March 4, 1920. Serial No. 363,258.

To all whom it may concern:
Be it known that I, BURR B. BLOOD, a citizen of the United States, and resident of Chicago, in the county of Cook and State 5 of Illinois, have invented certain new and useful Improvements in a Modifier for Phonograph Sound Boxes, of which the following is a description, reference being had to the accompanying drawing, which forms 10 a part of my specification.

My invention relates to a device whereby the tones or sounds produced by the reproducer or sound-box of a phonograph may be readily modified; that is the volume of 15 the tones, reduced or moderated without, however, affecting the tone quality; the object of the invention being to provide means whereby the modifying of the tones or sounds may be quickly accomplished with- 20 out necessitating any change or alteration in the sound-box or reproducer, per se; the invention comprising means whereby the tones or sounds may be modified without dissipating the tones as is the case with many 25 modifiers at present in use.

The invention contemplates means adapted to be readily secured to any of the well known types of sound-boxes at present employed and which may be easily adjusted to 30 the varying sized sound-boxes or reproducers in use.

The objects and advantages of my invention will be readily comprehended from the 35 following detailed description of the accompanying drawing, wherein:—

Figure 1 is a front elevation of a sound-box or reproducer with my improved modifier attached thereto.

Figure 2 is a sectional view taken on the 40 line 2—2 of Figure 1, looking in the direction of the arrows.

Figure 3 is a perspective view of the modifier, unattached to a sound-box.

Figure 4 is a front elevation of a sound- 45 box or reproducer illustrating a modified form of my invention.

Figure 5 is a fragmentary view of a portion of the sound-box and modified form of modifier mechanism shown in Fig. 4.

50 My improved sound-controlling device or modifier is intended to be adjustable to the usual style of reproducers or sound-boxes at present in use, which are usually provided with a circular shell or casing 10, composed 55 of front and rear portions removably secured together to permit the insertion of

the flexible diaphragm or mica 11, which is usually firmly held at the perimeter between two non-metallic or rubber rings 12, 12, as shown in Figure 2. The shell or casing 10 60 on its perimeter is shown provided with a pair of parallelly disposed and properly spaced apart lugs as at 13, 13, between which the cross-head or piece 14 of the stylus-bar 15 is pivotally mounted, in order that the 65 vibrations or movements encountered by the stylus or needle (not shown), carried in the socketed end of the stylus-bar may be freely transmitted to the flexible or mica diaphragm 11 by the upper end of the stylus- 70 bar 15 which is firmly attached to the flexible diaphragm. The parts that have thus far been referred to are the usual elements of a sound-box and therefore need no further specific description as they form no part of 75 my present invention.

As is well known, the reproduced tones or sounds are the result of the flexing of the mica or flexible diaphragm 11 whereby varying degrees of impulses are set up in 80 the air space or chamber within the sound-box, rearward of the mica or flexible dia- phragm 11; the volume or degree of the sound-impulses depending upon the degree 85 of flexure or vibrations imparted to the flex- ible or mica diaphragm 11 and the amount of flexing area presented by the flexible or mica diaphragm 11.

My invention comprises a mica or flexible diaphragm-engaging member 16, which is 90 preferably in the nature of a metallic ring provided with a cut-out portion or opening as at 17 for the passage of the stylus-bar 15, which is usually secured at a central point on the diaphragm 11. The member 95 16 is preferably of metal and the lower sur- face or side disposed toward the diaphragm 11 is provided with a cushion 18 composed of soft fabric or material which may be se- 100 cured in any suitable manner to the mem- ber 16; as for example, the member 16 may be provided with a groove, disposed circuit- ously throughout the lower side, in which a ring of rubber, felt or other soft fabric 105 may be embedded, so that a more or less yielding pressure on the flexible diaphragm will be provided when the member 16 is forced toward the diaphragm.

The member or ring 16 is secured to one 110 arm of an angular lever or element 19 which is pivoted at 20 between the bifurcations 21 of an attaching clamp 22.

The clamp or member 22 is intended to fit about the edge of the casing 10 of the sound-box so as to have the ring 16 disposed substantially parallel with the forward side 5 of the flexible diaphragm. In order to permit the bracket or member 22 to be clamped onto the sound-box, the bracket 22 is shown provided with the two depending and spaced apart portions 23 and 24, which are adapted 10 to engage with opposite sides of the casing as shown in Fig. 2; the spacing between the portions 23 and 24 being preferably slightly greater than the thickness or depth of the casing of the usual reproducer or sound-box. The portions or lugs 23 and 24 are of length sufficient to enable suitable purchase on the casing; and the portion or lug 24 is shown preferably provided with a thumb or set-screw 25 which extends there- 15 through and is adapted to engage with the casing of the sound-box when screwed inwardly and thereby firmly secure the bracket or clamp member 22 to the sound-box. The lobes or bifurcations 21 of the bracket or 20 clamp member extend slightly forward of the lug 23 as clearly shown in Figures 2 and 3, so as to permit the depending arm of lever or member 19 and the member 16 to normally be disposed slightly forward of 25 the sound-box and out of contact therewith. The upper arm of angular member or lever 19 is disposed substantially parallel with the top of the clamp member or bracket 22. The lever or angular member 19 is so 30 formed and mounted that the upper arm will normally have spaced relation with the clamp member or bracket 22, thus enabling slight tilting movement of the lever 19 when desired.

40 Intermediate of the depending arm of the lever 19 and the lug or portion 23 of the clamp member 22, I prefer to provide a small coil spring 26, see Figure 2, which tends to force the depending arm of angular 45 lever 19 and the member or element 16 away from the forward side of the sound-box, so that the normal direction of movement of element 16 is away from the flexible or mica diaphragm. The action of the coil 50 spring 26 will therefore cause the angular lever 19 to swing on its pivotal point 20 and induce the upper arm of the lever to move toward the bracket or clamp member 22. In order to control the action of lever 19 and 55 therefore regulate the relation of the member or ring 16 to the diaphragm, I provide the upper arm of the lever 19 with a thumb or set-screw 27, adapted to screw through a tapped opening which is preferably ar- 60 ranged near the end of the arm so that rapid and greater regulation of the lever 19 and member or ring 16 may be obtained. The screw 27 is intended to screw through the upper arm of the lever 19 and engage with 65 the top or adjacent surface of the bracket

or clamp-member 22; it being apparent that the farther the screw 27 is screwed through the arm, or rather the greater the length of the screw disposed between the arm of the lever and the bracket or clamp-member, the 70 greater will be the separated relation between the bracket and the upper arm of the lever and therefore the closer will the depending arm of the lever 19 and the ring or member 16 be moved toward the flexible or mica diaphragm 11 of the sound-box. 75

In practice, the modifier is secured to the sound-box by placing the bracket or clamp member 22 at any convenient point on the perimeter of the sound-box, so that the cut-out portion or opening 17 in the member or ring 16 will coincide with the stylus-bar 15 of the reproducer, while the lugs 23 and 24 are arranged on opposite sides of the sound-box. The modifier having been properly positioned, thumb-screw 25 is then screwed inwardly into engagement with the rear side of the sound-box and the bracket or clamp-member thereby firmly held in position. 80

If it is desired to reduce or modify the 90 tones or sounds of a selection, namely if it is intended to diminish or soften the tones, the ring or member 16 is then forced or made to move into contact with the flexible or mica diaphragm through the proper turning of 95 thumb-screw 27, that is by screwing thumb-screw 27 inwardly against the bracket or clamp-member 22 so as to increase the distance between the bracket and the arm of the lever 19. This action will cause the depending arm of the lever 19 with ring or member 16 to be moved toward the flexible diaphragm; the amount of pressure on the diaphragm determining the degree of tone 100 or sound modification. It is apparent, that the firmer ring 16 is brought into contact with the diaphragm, the less flexing will be possible through the action thereon of the stylus-bar and hence the softer or more subdued will be the tones or sounds; as the relation of the member 16 to the diaphragm 105 will control the flexing area of the latter. 110

I prefer to have the ring or member 16 disposed substantially concentric with the center of diaphragm 11 and therefore have 115 shown the ring or member 16 as adjustably secured to the depending arm of the lever 19, so as to adapt the modifier to different sized sound-boxes.

In the exemplification, the ring or member 120 16 is formed with a pair of spaced lugs 28, 28 between which the depending arm of the lever 19 extends, and this arm is shown provided with a slot 29 disposed lengthwise thereof. 125

A set-screw 30 is disposed through the slot 29 of lever 19 and screws into the member 16 or lug thereof; so that after the ring 16 has been positioned so as to bring it substantially concentric with the center of the dia- 130

phragm, the set-screw 30 is then screwed tightly, causing its head to firmly grip the lever on opposite sides of slot 29.

In Figure 4 I show a modified form of my invention wherein the shell or housing of the sound-box 10, namely the front side of the rim portion, is provided preferably with a pair of spaced lugs 31 formed integral therewith; the lugs 31 being provided with 10 aligned apertures to receive a pivot-forming member 32 whereby the angular member or lever 33 is pivotally secured in place, to permit the lever to oscillate in a direction substantially at right angles to the front 15 face of the sound-box.

The angular construction of lever 33 may be identical with the construction of the lever shown in Figure 3; with one arm of the lever 33 being disposed transversely of 20 the periphery or rim of the sound-box. This transversely disposed arm is provided with an adjusting member or thumb-screw 34 adapted to screw through the arm of the lever and engage with the rim or shell of the 25 sound-box. The other arm, namely the arm disposed substantially parallel with the front face of the sound-box, terminates in the perimetric portion 35, similar to that shown in the previous figures; the portion being 30 preferably in the nature of a ring and provided with a slit or cut-away portion for the passage of the stylus-bar 15 of the sound-box. In practice, the lugs 31 are disposed at a point where they will be located at what 35 may be termed the top edge of the sound-box when the latter is in playing position, so that any pressure caused by the hand of the operator in manipulating the regulating member or screw 34 while the sound-box is 40 traveling across the record will be in a direction as not to interfere with the movement of the sound-box nor cause the stylus or needle to slide across and damage the record. With the modifier pivoted to the shell of 45 the sound-box, as previously described, manipulation of the regulating member or screw 34 and therefore adjustment of the modifier during movement of the sound-box may be easily accomplished. The arm of the 50 lever 33, provided with the portion 35, like in the previously described construction, is intended to be normally held outward or away from the front face of the sound-box and therefore in spaced relation with the 55 flexible diaphragm of the sound-box by a suitable spring 36 which may be disposed between the shell of the sound-box and the arm of the lever at a point beneath the pivotal point 32, so that the normal tendency 60 of the spring will cause the arm of the lever which is disposed transversely of the edge or rim of the sound-box to come into close relation therewith, except when the regulating member or screw 34 is turned so as to have 65 the inner end of the screw engage with the

shell of the sound-box, which forces the arm upward or away from the rim of the sound-box and thereby swings the other arm with portion 35 toward the flexible diaphragm.

The constructions shown and described, I believe to be simple adaptations of the invention, but modifications may be made in certain details which I believe would still embody the principles of my invention.

What I claim is:—

1. A modifier of the class described, comprising, in combination with a phonograph sound-box having a flexible diaphragm and stylus-carrying member, a supporting bracket adapted to fit about the peripheral edge 80 of the shell of the sound-box, means whereby the bracket may be removably clamped in place, a lever pivotally secured to said bracket so as to have one end thereof swing toward or away from the diaphragm of the 85 sound-box, a diaphragm engaging ring adjustably secured to said lever and provided with a cut-away portion for the passage of the stylus-carrying member, and regulable means coacting with said lever and said 90 bracket whereby the position of said ring relative to the diaphragm may be controlled.

2. A modifier of the class described, comprising an attaching bracket adapted to 95 clamp onto the peripheral edge of the shell of a phonograph sound-box, a lever pivoted intermediate of its ends on said attaching bracket so as to have one end of the lever disposed radially at the forward side of the 100 sound-box, an annular member secured to said last mentioned end of the lever and adapted to engage with the flexible dia- phragm of the sound-box, said last mentioned member having an open center and 105 cut-away portion in the periphery thereof for the passage of the stylus-carrying mem- ber of the sound-box, means whereby said last mentioned member is normally held away 110 from the flexible diaphragm of the sound- box, and means whereby said annular mem- ber may be brought into engagement with the flexible diaphragm with regulable pres- sure.

3. A modifier of the class described, comprising, in combination with a phonograph sound-box provided with a diaphragm and a stylus-carrying member, means adapted to fit about the peripheral edge of the shell of the sound-box with a portion thereof dis- 115 posed into a plane forward of the plane of the front edge of the shell of the sound-box, a lever pivoted intermediate of its ends on said forwardly presented portion of said means so as to have one end of the lever ex- 120 tend forward of the front face of the sound- box and substantially parallel therewith, a ring secured to said last mentioned end of the lever and provided with a cut-away por- 125 tion adapted for the passage of the stylus- 130

carrying member, the under surface of said ring being provided with cushion-providing material adapted to contact with the diaphragm of the sound-box, and regulable means whereby the position of said ring, relative to the diaphragm, may be controlled.

4. A modifier of the class described, comprising, in combination with a phonograph sound-box provided with a flexible diaphragm and a stylus-carrying member, an attaching member adapted to fit onto the peripheral edge of the sound-box, said member being provided with a forwardly presented pivot-providing portion, an angular lever pivoted intermediate of its ends to said portion so as to have one end of the lever disposed in a radial manner forwardly of the sound-box, a ring adjustably secured to said last mentioned end of the lever and adapted to be concentrically arranged with the center of the flexible diaphragm, said ring being provided with a cut-away portion adapted for the passage of the stylus-carrying member of the sound-box, and means whereby the position of said ring relative to the flexible diaphragm may be controlled.

5. A modifier of the class described, comprising an attaching member adapted to be disposed about the peripheral edge of a phonograph sound-box, said member having a pivot-providing portion disposed into a plane forwardly thereof, an angular lever pivoted intermediate of its ends to said portion, with the ends of the lever being disposed in proximity to different sides of said attaching member, a spring disposed intermediate of one side of said member and one end of said lever whereby the latter is normally held away from said side of the member, a ring secured to the last mentioned end of said member and adapted to be disposed forward of the flexible diaphragm of a sound-box, the rear side of said ring being provided with a cushion-providing element, while the ring has a cut-away portion for the passage of the stylus-carrying member of the sound-box, and manually operable means secured to the other end of said lever whereby the tilt of said lever and the position of said ring relative to the flexible diaphragm of the sound-box may be controlled.

6. A modifier of the class described, comprising an attaching portion adapted to fit onto the edge of a phonograph sound-box, a member pivoted to said portion so as to adapt it to extend in a radial direction in front of the sound-box, a circular member adjustably secured to the first member and provided with an opening adapted for the passage of the stylus-carrying member of a sound-box, means whereby said circular member is normally held in a forwardly swung position, and regulable means whereby the circular member may be forced in a

direction opposite to that induced by said first means.

7. A modifier of the class described, comprising a phonograph sound-box, the shell or casing whereof is provided with a pair of spaced lugs, an angular member pivoted between said lugs so as to have one end of said member move at an angle to the front face of the sound-box, said end terminating in an annular portion or ring of smaller diameter than the inner diameter of the peripheral flange at the front of the sound-box, said portion or ring being provided with a slot or cut-out portion for the passage of the stylus-bar of the sound-box and adapted to engage with the flexible diaphragm of the sound-box and thereby provide a smaller flexing area in the diaphragm, means whereby said portion or ring is normally held out of contact with the diaphragm, and means whereby the position of said portion or ring relative to the diaphragm may be controlled.

8. A modifier of the class described, comprising, in combination with a phonograph sound-box having a flexible diaphragm, pivot-providing means arranged on the rim of the sound-box, means pivotally secured to said first means so as to swing toward and away from the diaphragm, said last means including a perimetric portion adapted to provide a restricted flexing area in the diaphragm bounded by said portion, means whereby the perimetric portion is yieldingly held out of operative position, and regulable means whereby movement of the second means may be controlled and the position of the perimetric portion relative to the diaphragm determined.

9. A modifier of the class described, comprising a sound-box provided with a flexible diaphragm, the rim whereof is provided with a pivot-providing portion, means pivotally secured to said portion to oscillate toward and away from the diaphragm of the sound-box, said means including an angular arm having one part disposed transversely of the rim of the sound-box and a second part disposed substantially parallel with the diaphragm of the sound-box, and a perimetric portion adjustably secured to the second mentioned part of said angular arm, said perimetric portion being adapted to provide a restricting flexing area in the diaphragm bounded by said portion, a spring acting on said angular arm to normally hold the perimetric portion out of contact with the diaphragm, and regulable means operatively connected with said arm whereby the position of the perimetric portion relative to the diaphragm may be regulated.
